LOCK

Julius H. Kintzele, St. Louis, Mo., assignor to
 Pauly Jail Building Company, St. Louis, Mo.,
 a corporation of Missouri

Application September 2, 1930. Serial No. 479,141

4 Claims. (Cl. 70—47)

This invention relates to locks, and has special reference to locks of the multiple tumbler type; and an object of the invention is to provide an improved lock of the multiple tumbler type comprising a rotary actuator for moving a lock bolt and a series of tumblers movable approximately parallel with the axis of the actuator to positions to permit and to prevent rotation of said actuator, in combination with a key member for moving said tumblers.

Another object of the invention is to provide an improved lock possessing all of the advantages of the lock herein disclosed, reference being made to the accompanying drawings, in which—

15 Fig. 1 is a side elevation of my improved lock.
 Fig. 2 is a sectional view of the lock casing showing the lock bolt projected.

Fig. 3 is a vertical transverse sectional view of the lock.

20 Fig. 4 is a vertical sectional view of the lock casing showing the tumblers in end elevation and the guides for said tumblers in section.

Fig. 5 is a sectional view of the lock casing and the rotary actuator for the lock bolt.

25 Fig. 6 is a detail sectional view of a portion of the lock showing one of the tumblers in unlocked position.

Fig. 7 is a similar view showing the tumbler pushed too far from its normal position so that it will lock the bolt actuator against movement.

30 Fig. 8 is a side elevation of the key showing the series of projections for operating the lock tumblers to position to permit turning movement of the actuator for the lock bolt.

Fig. 9 is a side edge elevation of the lock key.
 Fig. 10 is a view showing one of each of several series of lock tumblers.

In the embodiment of the invention shown, my improved lock comprises a plate 1 which may be a metallic door or may be a separate element attached to a door. A housing is rigidly attached to said plate 1 and comprises a metallic member shaped to provide an outer wall 2, side walls 3, an end wall 4, and an opposite end wall 5 having therethrough an opening for projection and withdrawal of the locked bolt. The walls 3 and 4 are formed with a continuous laterally extended flange 6 which seats against the wall member 1 and is rigidly attached thereto by appropriate fastening means such as rivets 7.

45 The plate 1 supports a series of laterally extended posts 8 of strong and rigid construction, having therein circumferential grooves 9 in which the lock bolt 10 is mounted for longitudinal sliding movements to and from locking position.

Thus, the posts 8 and the grooves 9 therein constitute supports and guides for the lock bolt 10, so that said lock bolt is properly guided and supported in its movements and cannot become disarranged.

50 A barrel 11 is rotatively supported by the plate 1. Said barrel 11 is mounted in a hole in the plate 1 and is formed with a circumferential flange 12 seating against the side of said plate that is covered by the housing wall 2. Said flange 12 is engaged in a groove formed in a ring 13 that is rigidly secured to the plate 1 by rivet fasteners 14 or other appropriate fastening means. The ring 13 is formed with an annular flange 15 that encircles the inner end of the barrel 11 and has, at its inner end, an inwardly extended flange 16 extending across the peripheral portion of the inner end of said barrel 11 (Figs. 3 and 4). Thus, the barrel 11 is free to turn in its support comprising the plate 1, the ring 13, the flange 15 and the flange 16.

55 The barrel 11 is operatively connected with the bolt 10 and is manipulative to move said bolt 10 to and from locking position. An appropriate form of connection for this purpose is shown, the same comprising a plate 17 rigidly attached to the inner end of the hub 18 of the barrel 11 by a fastener 19, and having a crank pin 20 projecting into a slot 21 in the lock bolt 10. Thus, it is apparent that turning of the barrel 11 from a starting position will project the lock bolt 10 to locking position, and turning of the barrel 11 to its starting position will move the lock bolt 10 from locking position.

60 The plate 17 has its edge extended toward the plate 1 to form a skirt 22. The edge of the skirt 22 terminates near but out of contact with the end of the flange 15. It is now clear that the actuator described comprises a crank that is rotative about an axis of the barrel 11 from 65 and to a starting position. The starting position may be considered that position in which the crank pin 20 holds the lock bolt 10 retracted within the lock housing, in which position said lock bolt is out of locking position. Turning 70 of the actuator in one direction from this starting position moves the lock bolt outwardly to locking position, which is clearly shown in Fig. 2 of the drawings. The grooved construction of the rigid posts 8 constitutes supports and guides 75 for supporting and guiding the lock bolt in these movements and for positively preventing the lock bolt from becoming disarranged or dislocated.

75 The barrel 11 is provided with a circular series of holes, each comprising an inner enlarged 80

portion 23 and an outer portion 24 in axial alignment with and of smaller diameter than the inner portion 23. This construction provides an annular shoulder 25 at the communicating ends of the hole portions 23 and 24. In each of these holes a cylindrical tumbler is mounted. Each tumbler comprises an enlarged inner portion 26 separated from an enlarged intermediate portion 27 by a circumferential groove 28; and an outer portion 29 of less diameter than the portions 26 and 27. Each of these tumblers is mounted in a hole 23, 24 and is normally held in position in which the outer ends of the enlargements 27 seat against the shoulders 25. In such positions, the reduced outer portions 29 of these tumblers are in the hole portions 24, the outer ends of the tumblers being approximately flush with the outer surface of the plate 1. The flange 16 is formed with a series of notches 30 having curved walls in continuation of the walls of the hole portions 23. In the outer positions of the tumblers, the inner enlarged portions 26 of said tumblers are engaged in the notches 30. When the tumblers are thus engaged in the notches 30, it is impossible to rotate the barrel 11 because the member in which the notches 30 are formed is rigidly attached to the plate 1 by the fasteners 14 or otherwise. In order to permit rotation of the barrel 11, it is necessary to move all of the tumblers inwardly until the grooves 28 are opposite the flange 16. The notches 30 are deep enough to disengage the tumblers from the flange 16 and permit rotation of the barrel 11.

The tumblers are tubular, being open at their inner ends and closed at their outer ends (Fig. 3). Pins 31 rigid with the plate 17 project into the inner ends of the respective tubular tumblers. Coiled springs 32 have their inner ends bearing against the plate 17 and encircling the pins 31. These springs extend outwardly into the respective tumblers, having their outer ends bearing against the outer end walls of said tumblers and thus actuating the tumblers outwardly to positions in which the ends of the circumferential portions 27 of said tumblers abut against the shoulders 25. In such position of the tumblers, the parts 26 of said tumblers are seated in the notches 30, thus positively locking the barrel 11 so that the lock mechanism cannot be manipulated. The construction and arrangement and relationship of these parts are such that, in either the inner or outer position of the lock bolt 10, the tumblers can assume locking positions in which the tumbler parts 26 are in the notches 30 and thus prevent operation of the lock.

As clearly shown in Fig. 10 of the drawings, the grooves 28 are at different distances from the inner ends of the respective tumblers, thus leaving the tumbler portions 26 of the respective tumblers of different lengths. Because the tumblers themselves are of the same length, this construction requires that the tumblers be pressed inwardly different distances according to the distances of the grooves 28 from the inner ends of the respective tumblers, in order to disengage the tumbler portions 26 from the notches 30 and to place the grooves 28 in registration with the notches 30 and, therefore, in registration with the flange 16 to unlock the barrel 11 so that said barrel 11 can be rotated. If any tumbler be moved too far its portion 27 will engage the notch 30 and lock the device. It is clear that these tumblers may be located in any arbitrary position and that

the tumblers in one lock may be located in different relationship than any other locks, so that the same key device cannot be used for opening different locks.

A key device for opening this lock is sufficiently shown in the drawings, comprising a handle 33 having a post 34 projecting laterally from one end portion thereof and rigidly supporting a plate 35. The plate 35 has a pair of peripheral projections 36. A series of lugs 37 project from the plate 35 oppositely from the handle 33 and are arranged and located so that, when the post 34 is inserted in the hole 38 of the barrel 11, said lugs 37 may be brought into registration with the tumbler ends 29. These lugs 37 are of different lengths according to the lengths of the tumbler portions 26, so that proper application of the key will press all of the tumblers inwardly a distance sufficient to disengage the tumbler portions 26 from the notches 30 and to place the grooves 28 in registration with the flange 16, thereby to permit rotation of the barrel 11 and operation of the lock bolt 10.

A ring 39 is rigidly attached to the plate 1 by the same fasteners 14 that attach the member 13 to said plate 1. The ring 39 has an inwardly extended flange 40 provided with spaced notches 41 through which the projections 36 may pass in order to permit application of the key to operate the lock.

In applying the lock, the post 34 is inserted in the hole 38 and the projections 36 are caused to pass through the notches 41, thus locating the lugs 37 in alignment with the tumbler ends 29. The key is moved inwardly until the plate 110 35 engages against the outer end of the barrel 11, thereby causing all the lugs 37 to move inwardly corresponding tumblers to positions in which the grooves 28 of all the tumblers are in registration with the flange 16, in which position the barrel 11 is unlocked and may be turned. In such position of the key, the lugs 37 being engaged in the hole portions 24, will rotate the barrel 11 and thereby the plate 17 and the crank pin 20, and thus move the lock bolt 10 outwardly to locking position, which is shown in Fig. 2 of the drawings. According to the construction shown, it is impossible to detach the key from the lock when the lock bolt is retracted or unlocked, because the projections 36 are engaged under the flange 40. However, when the key is operated to rotate the barrel 11 to position in which the lock bolt is extended outwardly to locking position, the projections 36 are opposite the notches 41 and the key may be detached.

It will be understood that the location and relative arrangement of the long and short lugs 37 will be varied according to the variation in the location and arrangement of the tumblers. This variation in the arrangement of the lugs 37 is necessary in order that the long lugs 37 may be brought into engagement with the outer ends of the tumblers having long tumbler portions 26, etc.

It is now clear that my improved lock is designed and adapted for uses in any place in which it is desired to provide a lock that cannot be easily opened or manipulated by unauthorized persons. The tumbler construction being concealed, it is impossible for any unauthorized person to know the extent to which the respective tumblers must be moved inwardly in order to register the tumbler grooves 28 with the flange 16. The movement of the tumblers is not accompanied by any noise or sound indicating the

released positions of the tumblers, so that there is no possibility of any unauthorized person manipulating and releasing the lock.

The construction, arrangement and relationship of the parts may be varied otherwise than as specifically suggested without departure from the nature and principle of the invention. I do not restrict myself in any unessential respects, but what I claim and desire to secure by Letters Patent is:—

1. A lock comprising a support having a hole therein, a barrel mounted for rotation in said hole, a flange rigid with said support and extending across a marginal portion of the inner end of said barrel and having notches in its inner edge, a series of tumblers supported in said barrel for longitudinal movements parallel with the axis of said barrel and through said notches, a plate attached to said barrel and spaced beyond the inner end thereof and beyond said flange, and springs mounted between said plate and said tumblers holding said tumblers engaged in said notches in said flange.

2. A lock comprising a support having a hole therein, a barrel mounted for rotation in said hole, a plate attached to said barrel and spaced beyond the inner end thereof, a ring rigid with said support holding said barrel against longitudinal displacement, a flange rigid with said plate and extending into said space between said barrel and said plate and across a marginal portion of the inner end of said barrel and having notches in its inner edge, a series of tumblers supported in said barrel for longitudinal movements parallel with the axis of said barrel and through said notches and having grooves adapted to receive said flange, and springs mounted in connection with said plate and actuating said tumblers outwardly to position in which said tumblers are engaged in said notches.

3. A lock comprising a support having a hole therein, a barrel mounted for rotation in said

hole and having an annular series of holes therein, each of said last named holes comprising an inner enlarged portion and an outer portion in axial alinement with and of smaller diameter than said inner portion, a plate attached to said barrel and spaced beyond the inner end thereof, a flange rigid with said support and extending into said space between said barrel and said plate and across a marginal portion of the inner end of said barrel and having notches in its inner end, tumblers supported in said holes in said barrel and adapted to engage in said notches and thereby hold said barrel from turning and having notches adapted to receive said flange and thereby disengage said tumblers from said flange, reduced portions on the outer ends of said tumblers extending through said smaller portions of said holes in said barrel, and springs in connection with said plate actuating said tumblers outwardly to position in which said tumblers are engaged in said notches in said flange.

4. A lock comprising a support having a hole therein, a barrel mounted for rotation in said hole and having an annular series of holes, a plate attached to said barrel and spaced beyond the inner end thereof, a flange rigid with said support and extending into said space between said barrel and said plate and across a marginal portion of the inner end of said barrel and having notches in its inner edge, a hollow cylindrical tumbler mounted in each of said holes in said barrel and each having a notch adapted to receive said flange when said barrel is to be rotated, pins rigid with said plate extending into said tumblers, and springs mounted on said pins and having their inner ends engaging said plate and their outer ends extending into said tumblers, and said springs acting to hold said tumblers in their outward positions and engaged in said notches.
